DESIGN FOR A DOLL

Mabel H. Siegfried, Los Angeles, Calif.

Application May 27, 1940, Serial No. 92,629

Term of patent 14 years

To all whom it may concern:

Be it known that I, Mabel H. Siegfried, a citizen of the United States and a resident of the city of Los Angeles, in the county of Los Angeles and State of California, have invented a new, original, and ornamental Design for a Doll, of which the following is a specification, reference being had to the accompanying drawing, forming part thereof.

In the drawing:

Fig. 1 is a front elevational view of a doll, showing my new design, and

Fig. 2 is a rear elevational view thereof.

I claim:

The ornamental design for a doll, substantially as shown.

MABEL H. SIEGFRIED.
